DESIGN FOR A DRAWER HANDLE OR SIMILAR ARTICLE

Donald A. Morand and William H. Null, Portland, Oreg.

Application May 8, 1937, Serial No. 69,249

Term of patent 7 years

To all whom it may concern:

Be it known that we, Donald A. Morand and William H. Null, citizens of the United States, residing at Portland, county of Multnomah, State of Oregon, have invented a new, original, and ornamental Design for a Drawer Handle or Similar Article, of which the following is a specification, reference being had to the accompanying drawing, forming part thereof.

Fig. 1 is a perspective view of a drawer handle or similar article showing our new design.

Fig. 2 is a side elevation of the handle.
Fig. 3 is an end elevation of the handle.
Fig. 4 is a plan view of one of the mountings detached from the handle portion shown in Figs. 1, 2 and 3.

We claim:

The ornamental design for a drawer handle or similar article, as shown.

DONALD A. MORAND.
WILLIAM H. NULL.
